UNITED STATES PATENT OFFICE

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE

METALLIC-PLATE WALL ELEMENT

Application filed August 9, 1928. Serial No. 298,574.

The invention relates to railway freight train cars and more particularly to metallic plate walls therefor, and consists in forming an integral strut-beam adjacent one side 5 margin of a metallic plate which is capable of sustaining considerable compressive forces longitudinally of its length (as a column), and also capable of sustaining forces normal to its length (as a beam). Such a construction eliminates the beam and/or post which is usually attached to one or more margins of a metallic plate when used as a wall.

Such a construction when used in house or roofed cars (such as box, automobile, 15 stock, etc.,) would eliminate the use of corner post or door post, or if the strut-beam is positioned horizontally, would eliminate the use of the end plate or end sill. When used in open top cars (gondolas) the corner 20 post could be dispensed with.

A further object of the invention is to provide such a metallic plate with integral corrugations which vary in length according to the formation of the integral strut-beam.

25 A further object is to so form the integral strut-beam so as to provide means of securing the nailing strip for the lining of the car.

Another object is to provide a metallic 30 wall of a railway car with a specific form of integral flange, which flange performs the usual function of the corner post, door post, end plate or end sill of a railway car.

In the drawings:—

35 Figure 1 shows a railway box car equipped with a typical application of my device.

Figure 2 is a side elevation of Figure 1.

Figure 3 is a section on line 3—3 of Figure 1.

40 Figure 4 is a section on line 4—4 of Figure 1.

Figure 5 is a perspective view of a metallic plate with one margin formed into an integral strut-beam according to my invention.

In Figures 1—4, inclusive, the construction is shown when used in a metallic end wall for a railway box car. The metallic plate is bent to form a straight flange 2 adjacent the central portion of the vertical 50 margin of the end wall, preferably adjacent the intermediate longitudinal frame members 3 (if any) of the car to which it is preferably secured by means of the straps 4 of Figure 2. This straight flange changes 55 to a Z shaped flange 5—11—12 at the upper and lower part of the end wall preferably adjacent the upper (6) and lower (7) longitudinal frame members (side plate and side sill respectively) of the car, to which members it is preferably secured by the gussets or straps 8—9. Securing means 10 also preferably attach the inner portions 11 of the Z section to the frame members, while the outer portions 12 thereof overlap the side 60 walls of the car. The Z sections secured to the frame members of the car with the integral angular section therebetween makes a very strong column to resist compression and torsional stresses and also provides a 65 very strong beam, restrained at its opposite ends, to resist horizontal forces, in either direction, i. e. parallel with either the side or end walls of the car, therefore, I call the structure an integral strut-beam.

If desired the filler 13 may be used and secured to the strut-beam by the bolts 14 so that the filler reinforces the strut-beam both as a column and as a beam.

It is well known in the art of car designing to corrugate a wall to enable it to better withstand or resist the stresses which exist in such a wall (see patents to Murphy-Sisson, 1,021,571, July 2, 1912 and A. E. Small, 1,638,172, August 9, 1927) but I preferably vary the length of such corrugations according to the formation of the strut-beam.

The corrugations are made as long as possible and terminate into metallic plate 90

adjacent the flange forming the strut-beam, leaving only a small portion (18—19) between the end of the corrugation and its supporting flange, therefore, the corrugations 17 which terminate adjacent the straight flange (2) portion of the strut-beam are longer than the corrugations 16 which terminate adjacent the Z section (11) thereof.

10 A corrugation is a beam and must terminate adjacent its supports so as to transmit its loads thereto.

The nailing strips 21 provide means of attachment for the usual lining boards 22 and are attached to the strut-beam at the upper and lower Z sections, respectively, preferably to the web portion 5 by bolts 23 and also preferably to the outer flanges 12 thereof by bolts 24. These bolts prevent the 20 nailing strip from twisting and otherwise getting out of place. The sheathing 25 is nailed to the nailing strip.

Figure 6 is a perspective view of a metallic plate with one margin formed into a strut-beam comprising a straight flange 2 forming an angular section adjacent the vertical center of the margin which gradually changes into a Z shaped section (5—11—12) at both the upper and lower parts of the 30 margin of the plate. The longer corrugations 17 and the relatively shorter corrugations 16 are also shown. The obliquity of the web portion 26 may be varied to suit conditions.

35 The drawings illustrate the preferred form of the invention, though it is to be understood that the invention is not limited to the exact details of construction shown and described, as it is obvious that various 40 modifications thereof within the scope of the claims will occur to persons skilled in the art.

I claim:

1. In a railway car; the combination of 45 upper and lower frame members, a metallic wall having an integral strut-beam formed at one margin thereof comprising a straight flange adjacent the center of said margin, said straight flange changing to a Z shaped flange adjacent said upper and lower frame members to which it is secured.

2. In a railway car; the combination of 55 upper and lower frame members, a metallic wall having an integral strut-beam formed at one margin thereof comprising a straight flange adjacent the center of said margin, said straight flange changing to a Z shaped flange adjacent said upper and lower frame members with the webs of the Z flanges 60 secured to said upper and lower frame members respectively.

3. In a railway car; the combination of 65 upper, lower and intermediate frame members, a metallic wall having an integral strut-beam formed at one margin thereof

comprising a straight flange adjacent said intermediate frame member to which it is secured, said straight flange changing to a Z shaped flange adjacent said upper and lower frame members to which it is secured.

4. A metallic wall having an integral strut-beam formed at one margin thereof comprising a straight flange adjacent the center of said margin, said straight flange changing to a Z shaped flange at the upper and lower parts of said margin. 70

5. A metallic wall having an integral strut-beam formed at one margin thereof comprising a straight flange adjacent the center of said margin, said straight flange changing to a Z shaped flange at the upper and lower parts of said margin, said wall formed with integral corrugations some of 80 which terminate into the plate adjacent said Z flanges and others of which are longer and terminate into the plate adjacent the 85 straight flange.

6. In a railway car; the combination of upper and lower frame members, a metallic wall having an integral strut-beam formed at one margin thereof comprising a straight flange adjacent the center of said margin, said straight flange changing to a Z shaped flange adjacent said upper and lower frame members to which it is secured at the upper and lower parts of said margin, said wall formed with integral corrugations some of 90 which terminate into the plate adjacent said Z flanges and others of which are longer and terminate into the plate adjacent the 95 straight flange. 100

7. A metallic wall having an integral strut-beam formed at one margin thereof comprising a straight flange, said straight flange changing to a Z shaped flange at the upper and lower parts of said margin, and a nailing strip secured to the upper and lower 105 Z flanges respectively.

8. In a railway car; the combination of a metallic wall having an integral strut-beam formed at one margin thereof, comprising a straight flange, said straight flange changing to a Z shaped flange at the upper and lower parts of said margin, and a nailing strip secured to the webs of the upper and 110 lower Z flanges respectively. 115

9. In a railway car; the combination of a metallic wall having an integral strut-beam formed at one margin thereof comprising a straight flange, said straight flange changing to a Z shaped flange at the upper and lower parts of said margin, and a nailing strip secured to the webs and outer portions 120 of the upper and lower Z flanges respectively.

10. In a railway car; the combination of upper and lower frame members, a metallic wall having an integral strut-beam formed at one margin thereof comprising a straight flange, said straight flange changing to a Z 130

shaped flange adjacent said upper and lower frame members with the inner portions of the Z flanges secured to said upper and lower frame members respectively.

- 5 11. In a railway car; the combination of upper and lower frame members, a metallic wall having an integral strut-beam formed at one margin thereof comprising a straight flange, said straight flange changing to a Z
10 shaped flange adjacent said upper and lower frame members with the inner portions of the Z flanges secured to said upper and lower frame members respectively, and the outer portions thereof overlapping the side wall
15 of the car.
